BOTTLE STOPPER LOCK

Frank Edward Vanderhoof, Greenwich, Conn.,
assignor to Frank Woodrow Vanderhoof,
Greenwich, Conn.

Application October 20, 1934, Serial No. 749,209
Renewed May 19, 1936

2 Claims. (Cl. 215—54)

This invention relates to bottle stopper locks, and constitutes an improvement over my pending United States patent application Serial No. 737,138, filed July 27, 1934.

The primary object of the invention resides in a bottle stopper which may be locked in the neck of a bottle to prevent unauthorized access to the contents of the bottle. This bottle stopper lock will be found useful in connection with bottles containing spirituous liquors, poisons, perfumes, medicines and other like substances to prevent tampering with the contents of the bottle unknown to the owner thereof.

In the above mentioned application, I provided locking engagement between the stopper and the inner walls of the neck of a bottle at two opposed points, and this invention distinguishes therefrom by reason of a construction which provides an even and equal locking engagement between the stopper and the bottle neck entirely therearound, so as to effect a tighter locking action and to more positively seal the contents of the bottle.

A further feature of the invention is the provision of a yieldable bottle stopper which normally may freely fit into the neck of a bottle, and the same expanded circumferentially by key actuated wedge means into tight frictional engagement with the walls of the neck of a bottle.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a fragmentary perspective view of the neck of a bottle showing my invention in use thereon, the actuating key being removed.

Figure 2 is a vertical longitudinal sectional view with the stopper in locked position within the neck of a bottle and showing the expander member in elevation.

Figure 3 is a vertical longitudinal sectional view on the line 3—3 of Figure 2, but showing the actuating key in position for use.

Fig. 4 is a side elevational view of the lock stopper per se.

Figure 5 is a vertical sectional view of the expander member and the wedge screw removed therefrom.

Figure 6 is a horizontal sectional view on the line 6—6 of Figure 5.

Referring to the drawing by reference characters, the numeral 10 designates my improved bottle stopper and lock in its entirety which in-

cludes a yieldable plug body 11 adapted to be constructed of rubber, cork or like material in which the inherent characteristic is such that the material may be expanded from a pressure within and upon release of such pressure the material will return to its normal position. Extending inwardly from the top of the body 11 centrally thereof, is a recess or socket 12, the same terminating short of the bottom wall of the body.

Cemented to or otherwise secured to the top of the body 11 and extended beyond the plane of the said body is a rigid cap 13 and fixedly secured to the cap and extending into the recess 12 is a metallic sleeve member 14. The lower or inner end of the sleeve member 14 is slit inwardly at 15 various radial points as at 15 to provide radially disposed resilient fingers 16, the normal tendency of the fingers being to assume a retracted position as shown in Figure 6 of the drawing.

The sleeve member 14 is internally screw threaded as at 17 inwardly from the top end and the threaded bore is of uniform diameter and formed upon the inner side of the resilient fingers 16 are beveled or inclined wedge faces 18. Threading into the screw threaded bore 17 of the sleeve member 14 is a wedge screw 19, the inner end of which is cone shaped as at 20 for wedging engagement with the inclined faces 18 when the wedge screw is screwed home against the said faces 18. The top end of the wedge screw is provided with a key socket 21 and which socket may be made from various configurations to receive different shaped keys. For manually actuating the wedge screw 19, a removable key 22 is provided, which key includes a handle portion 23 at one end and a key portion 24 at its opposite end for fitting into the key socket 21 whereby manipulation of the key may turn the wedge screw in either direction.

In the drawing, I have illustrated my improved bottle stopper and lock in association with the neck A of a bottle B, and normally the body 11 is of a size to freely fit into the neck A. After insertion of the plug body 11 and should it be desired to lock the stopper therein, the key 22 is engaged with the wedge screw 19 and the key turned to feed the screw 19 inwardly until the cone end 20 wedges against the inclined surfaces 18 of the fingers 16. Such wedging action causes the fingers 16 to expand outwardly and such expansion effects the similar expansion or distention of the yieldable plug body 11 circumferentially into tight frictional engagement with the inner walls of the neck A as best seen in Figures 2 and 3 of the drawing. Due to the circumferential expand-

ing of the yieldable plug body 11, a positive seal is effected between the stopper and the walls of the bottle neck, and a more effective seal and a more positive locking action results.

5 5 In the event that it is desired to remove the stopper, the key is again connected with the wedge screw 19 and the said screw turned to move the same outwardly, whereupon the natural tendency of the resilient fingers 16 is to become retracted

10 and the natural characteristics of the yieldable plug body 11 causes contraction of the said plug body, thus permitting the free removal of the stopper by grasping the cap 13 and pulling outwardly thereon.

15 15 While I have shown and described what I consider to be the most practical embodiment of my invention, I wish it to be understood that such changes and alterations as come within the scope of the claims may be resorted to if desired.

20 20 Having thus described the invention, what I claim as new and desire to secure by Letters Patent of the United States, is:—

25 25 1. A bottle stopper comprising a yieldable plug body, a rigid cap fixedly attached to the top of said plug body and extending beyond the plane of the sides of said plug body, a sleeve member fixed to said cap and opening through the outer side thereof and embedded centrally within said yieldable plug body, radially disposed expandable fingers formed on the inner end of said sleeve member, said sleeve member being uniformly internally screw threaded inwardly from its top

end, inclined wedge faces provided on the inner sides of said expandable fingers, and a screw threaded into the threaded portion of said sleeve member and provided with a conical wedge at its inner end for wedging engagement with the inclined faces on said fingers to expand said fingers and cause said plug body to be distended into frictional contact with the inner walls of the neck of a bottle.

5 5 2. A bottle stopper comprising a yieldable plug body, a rigid cap fixedly attached to the top of said plug body, a sleeve member fixed to said cap and opening through the outer side thereof and embedded centrally within said yieldable plug body, radially disposed expandable fingers formed on the inner end of said sleeve member, said sleeve member being uniformly internally screw threaded inwardly from its top end, inclined wedge faces provided on the inner sides of said expandable fingers, a screw threaded into the threaded portion of said sleeve member inwardly of the top thereof and provided with a conical wedge at its lower end for wedging engagement with the inclined faces on said fingers to expand said fingers upon inward screwing of said screw to cause said plug body to be distended into frictional contact with the inner walls of the neck of a bottle, a key socket provided in the upper end of said screw, and a removable key for operatively fitting into said key socket by which said screw may be manually turned.

FRANK EDWARD VANDERHOOF.
